UNITED STATES PATENT OFFICE.

JAMES BEGG, OF VENTURA, CALIFORNIA.

HORSESHOER'S TOOL-BOX.

SPECIFICATION forming part of Letters Patent No. 743,807, dated November 10, 1903.

Application filed May 9, 1903. Serial No. 156,485. (No model.)

To all whom it may concern:

Be it known that I, JAMES BEGG, a citizen of the United States, residing at Ventura, in the county of Ventura and State of California, have invented certain new and useful Improvements in Horseshoers' Tool-Boxes, of which the following is a specification.

The primary object of this invention is to provide a stand to replace the tool-box commonly used by farriers, so as to facilitate the work of shoeing horses and enabling the tools and nails and the like to be more conveniently reached and preventing mixing of the different sizes of nails where the boxes or cells are open, as in the ordinary tool-box.

A further purpose of the invention is the provision of a stand which can be readily handled and capable of being quickly pushed aside when required for any purpose, same being mounted upon casters or rolling supports. In its structural organization the stand comprises a base or platform mounted upon casters, a spindle projected vertically from the base, a tool-tray rotatably mounted upon the spindle and base, a nail-tray revolvably mounted upon the upper end of the spindle and subdivided to form a series of boxes or cells for receiving different sizes of nails, and a rotatable cover for closing all the boxes or cells with the exception of one, thereby preventing nails from one box getting into any other box or cell.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a tool-stand for horseshoers embodying the invention. Fig. 2 is a vertical central section thereof. Fig. 3 is a vertical section of the joint formed between the spindle, tool-tray, and base, the parts being illustrated on a larger scale.

Corresponding and like parts are referred to in the following description and indicated

in all the views of the drawings by the same reference characters.

The base 1 may be of any construction and design and is mounted upon caster-wheels 2 and is centrally apertured to receive the lower threaded end 3 of spindle 4, which is secured to the base by clamp-nut 5 and shoulder at the base of threaded end 3. The lower end 6 of portion of spindle 4 adjacent to threaded end 3 is made tapering or conical, as shown at 6, and is surrounded by cup 7, forming a housing to protect the joint formed between the tool-tray 8 and spindle 4. A collar 9 is provided near the upper end of spindle 4 to support nail-tray 10, and the upper extremity of the end portion above collar 9 is reduced and threaded to receive nut 11, which prevents vertical displacement of nail-tray 10 and its cover 12.

The tool-tray 8 is of circular outline and is centrally apertured to receive cone 6 of spindle 4, upon which said tool-tray is adapted to turn freely to enable any tool or article 75 to be brought within convenient reach of the smith. A sleeve 13 is secured in the central opening of tool-tray 8 and is slightly upwardly flared to fit cone 6 and is provided at its upper end with a thickened edge or 80 reinforcement to resist wear. The lower end of sleeve 13 projects slightly below tray 8 to space the latter from base 1, upon which the lower end of sleeve 13 rests. Washer 14 is interposed between base 1 and tool-tray 8 to 85 receive the wear and insure proper spacing of parts 1 and 8. The upper portion of sleeve 13 enters cup 7 and is housed thereby, said cup preventing injurious contact of the tools with sleeve 13 and preventing dirt and 90 foreign matter from entering the joint formed between sleeve 13 and cone 6.

Nail-tray 10 is preferably of circular outline and of less diameter than tool-tray 8 and is rotatably mounted upon the upper end of 95 spindle 4 above collar 9. Sleeve 15 is in line with a central opening of tray 10 and extends upward therefrom, and radial partitions 16 subdivide the tray into a series of 100 cells or boxes for reception of different sizes and makes of nails. The partitions 16 are rigidly attached at their inner ends to sleeve 15 and at their outer ends to the rim of the tray, thereby serving to brace said rim and

sleeve, as well as keeping the nails separated. Cover 12 is centrally apertured to receive upper end of spindle and is provided with handle 17 for convenience of rotating the cover 5 and manipulating the stand when it is required to shift same from one point to another. The outer edge of cover 12 is downwardly deflected to overhang and snugly fit upper edge of the nail-tray. A portion is cut 10 from a side of cover 12 corresponding to the shape of the nail boxes or cells, so as to expose any one of said boxes to admit of its contents being readily reached.

The component parts of the stand are constructed of metal in such a manner as to provide a substantial and durable article capable of withstanding the severe wear and rough handling to which tool-boxes for smiths and horseshoers are usually subjected. The 15 larger tools—such as the rasp, pincers, hammer, and clencher-block—are placed in tool-tray 8, and the cover of the nail-tray forms a convenient rest for the knife when the stand is in service. If from any cause it becomes 20 necessary to quickly push the stand aside, same may be effected by the foot of the smith, thereby leaving the hands free to manage the animal or for other purposes, the casters or rotary supports admitting of the operation being easily and successfully accomplished.

Having thus described the invention, what is claimed as new is—

1. A tool-stand comprising a base mounted

upon rotary supports, a spindle projected upward from said base, a tool-tray mounted on the spindle adjacent to and supported by the base, means on the spindle for preventing vertical movement of the tray and protecting the joint between the said spindle and tray, 40 a nail-tray rotatably mounted upon the upper end of the spindle and subdivided into cells or boxes, a cover for the tray loosely mounted upon the spindle for independent movement and having a portion cut from one side 45 to expose a cell or box of the nail-tray, a handle applied to the cover for turning the same and providing convenient means for carrying the stand, and securing means applied to the upper end of the spindle for preventing vertical displacement of the cover and nail-tray, substantially as set forth.

2. In a device of the character described, a base, a spindle secured to the base and projected upward therefrom and having a tapering portion, a tray centrally apertured and provided with a sleeve in line with said aperture and mounted upon the tapering portion of the spindle, and a cup on the spindle and housing the joint formed between said 55 tray and spindle, substantially as set forth.

In testimony whereof I affix my signature in presence of two witnesses.

JAMES BEGG. [L. S.]
